(57) **CLAIM**

The ornamental design for an aircraft as shown and described.

DESCRIPTION

FIG. 1 is a front perspective view of an aircraft;
FIG. 2 is a front elevation view thereof;
FIG. 3 is a rear elevation view thereof;
FIG. 4 is an elevation view thereof taken from the right side, the left side being a mirror image thereof and therefore not shown;

FIG. 5 is a top plan view thereof; and,

FIG. 6 is a bottom plan view thereof.

The broken lines immediately adjacent the shaded surfaces depict the bounds of the claimed design, whereas all remaining broken lines depict portions of the aircraft that form no part of the claimed design.
